CIRCUIT BREAKER

Paul Klein, Berlin, and Kurt Wulsten, Berlin-Charlottenburg, Germany, assignors to Westinghouse Electric & Manufacturing Company, East Pittsburgh, Pa., a corporation of Pennsylvania

Application April 1, 1933, Serial No. 663,922
In Germany April 1, 1932

20 Claims. (CL 200—89)

Our invention relates to circuit breakers and is particularly suitable for use with circuit breakers of the trip free type.

One object of our invention is to provide a circuit breaker which shall not remain in the closed position if the engaging contacts should be burned or otherwise damaged.

Another object of our invention is to provide an improved trip free circuit breaker which shall include means for automatically opening the circuit if the cooperating contact members become incapable of carrying the normal circuit current without excessive heating.

Another object of our invention is to provide a double toggle linkage for a circuit breaker where the toggle links are in straightened position when the circuit breaker is closed and transmit a large part of the opening bias to a fixed pivot so that only a small force is transmitted to the current responsive latch holding one link in closed position.

A further object of our invention is to provide an improved toggle-linkage, circuit breaker operating mechanism that shall be particularly suitable for use with circuit breakers wherein safety and reliability of operation are paramount requirements.

An additional object of our invention is to provide a latching structure for a circuit breaker comprising a cylindrical latching portion normally holding a latch member, with a notch through the cylindrical latching portion to permit movement of the latch member therethrough upon rotation of the cylindrical portion.

In carrying out these objects of our invention, we prefer to provide a circuit breaker mechanism which is biased to the open position by a constant force biasing means and which is held in the closed position partly by the reaction forces resulting from the contact pressure producing means. These forces are so adjusted that any appreciable decrease in the contact pressure, which must simultaneously reduce the reaction force resulting therefrom, allows the biasing means to open the breaker.

The features of our invention which we believe to be new are particularly pointed out in the appended claims. For a full understanding of the principles of our invention and one method of applying those principles, reference may be had to the accompanying drawing and specification, wherein;

Figure 1 is an elevational view, partly in section, of a circuit breaker embodying the principal features of our invention, the various structural

elements being shown in the open circuit position.

Fig. 2 is a sectional view on the line II—II of Fig. 1.

Fig. 3 is a sectional view on the line III—III of Fig. 1.

Fig. 4 is diagrammatic view showing the various structural elements of the circuit breaker in the closed position, and

Fig. 5 is a diagrammatic view similar to Fig. 4 showing the circuit breaker in the tripped position.

In this embodiment of our invention we provide a pivotally mounted switch member assemblage, a toggle linkage operating mechanism, a trigger for restraining the toggle linkage in the operative position, a trip device including a latch for releasably engaging the trigger, a spring for biasing the mechanism to the open position, and means which are partially dependent upon the pressure between the cooperating contact members for holding the mechanism closed against the action of the biasing spring.

Referring to the drawing, the circuit breaker, which is of the double-break, push button type, includes a base 1 of insulating material upon which is mounted a pair of terminals 3, a pair of stationary contact supports 5, and the frame member 6 which supports the assemblage of switch members 7, the toggle operating mechanism 8, and the trip device 9.

The assemblage of switch members 7 includes a pair of contact members 11 adapted to engage the cooperating stationary contact members 13 which are mounted on the contact supports 5, leaf spring supports 15 for the contact members 11, and a switch shaft 17 to which one end of each of the spring supports 15 is rigidly joined. Two support lugs 19 and 21 extend outwardly from the base member 6 and pivotally engage suitable pins 40 in the ends of the switch shaft 17. A crank member 23 is provided for connecting the assemblage of switch members 7 with the operating mechanism 8.

As mentioned previously, the circuit breaker is of the double break type, the current flowing in one terminal 3, through the associated support 5 and its contact member 13, thence through the cooperating moving contact 11, the spring support arm 15, the energizing coil 59 for the trip device 9, the other spring support arm 11, and finally through the other contacts 11 and 13 and the other support 5 to the second terminal 3.

The operating mechanism 8 is of the toggle linkage type and includes a push button or han-

idle member 25 of insulating material, a pair of toggle links 27 and 29, a trigger or cradle 31 which engages one end of the toggle linkage through a pivot pin 33, a connecting link 35 intermediate the operating handle 25 and the toggle links 27 and 29, and a spring 37 which biases the assemblage of switch members 7 to the open position. The operating handle 25 is provided with a guide pin 39 which is rigidly affixed thereto and which is adapted to cooperate with a suitable guide opening in the portion 41 of the frame 6. The toggle links 27 and 29 are connected to each other by the knee pivot pin 43 which also serves to connect the link 35 with the toggle. The upper end of the link 35 is pivotally fastened to the operating handle 25 through the agency of the pin 45. The pin 45 has the further function of acting as a stop to define the upward limit of motion of the handle 25 and its associated guide pin 39. One end of the toggle link 27 is pivotally fastened to the crank member 23 by a pin 47. A spring 49 is positioned about the guide pin 39 and as will be explained later, is utilized to secure the automatic opening feature.

The trigger 31 is pivotally supported on a pin 51 which engages a lug 53 projecting outwardly from the frame 6, and is provided with a portion 55 ending in a latch tip for engaging 30 the latch 57 of the trip device 9.

The trip device 9 is of the conventional solenoid type and except for the particular type of construction disclosed is not an important part of my invention. The coil 59 is supported upon 35 the main frame 6 and is, as mentioned before, electrically connected in series between the two spring contact arms 15 so as to be responsive to the current flowing in the controlled circuit. A tube 61 having a slot 63 (Fig. 1) therein extends into the center of the coil 59, and serves as a guide means for the moving armature which is biased to the unattracted position by a suitable spring. A pin 65 which is rigidly affixed to the armature extends through the slot 63 and engages the latch actuating member 67.

The cylindrical latch shaft 57 is pivotally mounted on two lugs 69 and 71 projecting outwardly from the frame 6, and is biased into the latched position by the spring 73, the projection 50 15 serving as a stop to limit its motion. The enlarged cylindrical end of the latch shaft 57 has a latch portion 77 which engages the cooperating portion 55 of the trigger 31 and which is offset from the center of rotation of the latch 55 proper and is thus movable to release the trigger when the latch is rotated in a clockwise direction (Figs. 1, 4 and 5). The offset latch portion 77 comprises the portion of the enlarged cylindrical end of the shaft 57 which remains after a notch 60 is provided in the shaft extending slightly more than half-way through the shaft as shown on the drawing. The straight edge of the latch portion 55 engages the enlarged end of the shaft tangentially so that the force exerted thereon is 65 radially of the shaft.

The circuit breaker is closed by a downward pressure on the operating handle 25, the spring 49 being compressed and tending to move the operating handle and the knee pivot pin 43 upwardly. The toggle linkage is moved from the position shown in Figure 1 to the position shown in Figure 4. During this movement the knee pivot pin is moved below the straight line position, thus locking the contacts closed as is done 70 75 by conventional toggle operated mechanism. As

the handle 25 is moved downwardly, the crank arm 23 is rotated counterclockwise; the trigger 31 is likewise rotated but in the clockwise direction, the end 55 engaging the latch portion 77 near the end of the closing operation.

The rotation of the crank arm 23 causes a tensioning of the spring 37 and, by rotating the switch shift 17, causes the movable contact members 11 to engage the stationary contact members 13 thereby bending the leaf spring contact supports 15 to supply the necessary contact pressure. The reactive force from this stressing of the contact supports 15 acts through the crank arm 23 and the toggle link 27 as a pressure on the knee pivot pin 43 of the toggle linkage, and, 15 because of the over center or locked position of the linkage, will have a component opposing the spring 49. This component in combination with the similar component resulting from the tensioning of the spring 37, is of sufficient magnitude, 20 when adequate contact pressure exists between the cooperating contact members 11 and 13, to hold the circuit breaker closed.

However, if excessive wear, burning or other damaging agencies have so altered the contact members that proper engagement therebetween is not obtained when the operating handle 25 is moved to the closed position, the circuit breaker will open automatically as soon as the handle is released, due to the inadequacy of the force component balancing the opening spring 49. This feature is of very great value in preventing continued use of damaged switches wherein the insufficient contact pressure may cause enough heating to constitute a dangerous fire hazard.

The opening operation under these conditions is substantially the reverse of the closing operation. The spring 49 lifts the knee pivot pin 43 above the center line of the link, the toggle then collapses upwardly drawing the trigger 31 with it, the spring 37 acting through the crank member to move the contacts to the open position. The projection 79 serves as a stop for limiting the rotation of the crank member 23.

It is important to note that movement of the 45 assemblage of switch members 7 beyond a predetermined point is equally effective in securing automatic opening of the circuit. This follows from the fact that the distance which the knee pivot pin 43 moves beneath the center line of 50 the toggle is proportional to the force opposing the biasing action of the spring 49. Thus, if the assemblage of switch members 7 rotates sufficiently far to reduce this distance below the minimum required to balance the knee biasing 55 force the breaker will not remain in the closed circuit position when the operating handle 25 is released.

In the event of an overload or other predetermined electrical condition, the coil 59 of the 60 trip device becomes energized sufficiently to attract its associated armature. The pin 65 (Fig. 3) engages the latch actuating member 67 and, by rotating the latch against its biasing spring 73, causes the portion 77 to disengage the trigger 31. 65 The entire toggle linkage is then free to move to the open position under the influence of the stressed spring supports 15 and the spring 37. If the handle is not held down the spring 49 returns the various parts of the mechanism to the 70 position shown in Figure 1. If an attempt is made to hold the circuit breaker closed the mechanism moves, following the tripping operation, to the position shown in Figure 5, the mechanism being entirely trip free.

5 A manual release mechanism is also provided. This includes a member 81 which is slidably supported on a lug 83, biased upwardly by a spring 85, and provided with an operating button 87 of insulating material. When the member 81 is depressed it engages the latch operating member 87 and through it rotates the latch 51 to the unlatched position, the breaker opening in exactly 10 the same manner as described in the paragraph relating to the operation of the trip device. The breaker may also be opened manually by moving the operating handle 25 away from the base 1.

15 The release mechanism, however, assures the rapid separation of the engaging contact members and is the preferred method of operation.

20 It will thus be seen that we have disclosed an improved circuit breaker operating mechanism which automatically opens the circuit if the contact members are burned or damaged, or if the contact pressure is inadequate to prevent dangerous overheating, and in addition, we have disclosed how this feature of our invention may be embodied into a circuit breaker of the trip-free type.

25 Further, we have disclosed a novel circuit breaker operating mechanism of the toggle linkage type which is more reliable and more satisfactory in operation than the previously known devices.

30 The principles which we have disclosed are capable of wide application to circuit breakers generally, and it is our desire that the language of the accompanying claims shall be accorded the broadest reasonable construction, and that our invention shall be limited only by what is explicitly stated in the claims and by the prior art.

I claim as my invention:

1. In a circuit interrupter, a stationary contact member, a movable switch means including a contact member for cooperating therewith to open and close the electrical circuit through said interrupter, spring means for supplying contact pressure between said cooperating members when said interrupter is in the closed position, and an operating mechanism for actuating said switch means, said operating mechanism including a toggle linkage, means biasing the knee of said linkage to the open circuit position, and means responsive to the contact pressure between said cooperating members for holding the knee of said toggle in the closed circuit position against said biasing means, said holding means being releasable and causing the movable contact member to move to open circuit position upon a predetermined decrease in contact pressure between said cooperating members.

2. In a circuit interrupter, a stationary contact, a switch member having a moving contact for cooperating with said stationary contact for opening and closing the electrical circuit through said interrupter, and an operating mechanism for actuating said switch member, said operating mechanism including a toggle linkage, means for biasing the knee of said toggle to the open circuit position, and means operable upon change in the contact pressure between said contacts to cause said biasing means to move the knee of said toggle and said switch member to open circuit position.

70 3. In a circuit interrupter, a butt contact member, a movable switch means including a contact member for making butt engagement with said butt contact and movable to open and close the electrical circuit through said interrupter, an operating mechanism for actuating said switch

means, a spring for biasing said switch means to the open position, said operating mechanism including means separate from said butt contact members operable to lock said switch means in the closed circuit position, and said locking means being operable only when there is a predetermined contact pressure between said butt contact members.

4. In a circuit interrupter, a stationary contact member, a pivotally supported switch member, including a contact and a leaf spring support for said contact, for cooperating therewith to open and to close the electrical circuit through said interrupter, and an operating mechanism for actuating said switch member, said operating mechanism including a pair of toggle links pivotally joined together at one end by a knee pivot pin, the other end of one link operatively engaging said switch member and the other end of the second link engaging a releasable trigger normally held by current responsive means, spring means biasing said knee pivot pin to the open circuit position, and means responsive to the movement of said switch member beyond a predetermined point for holding the knee of said toggle in the closed circuit position against said biasing means, said knee pivot pin, when said interrupter is in the closed circuit position, being free to move under the biasing action of said spring to the open circuit position when released by said holding means.

5. In a circuit interrupter, relatively movable contact means for opening and closing the electrical circuit through said interrupter, one of said contact means including a switch member, spring means biasing said switch member to the open circuit position when said interrupter is in the closed circuit position, and an operating mechanism for actuating said switch member, said operating mechanism including a toggle linkage and a bell crank having one arm pivoted to one end of said toggle linkage, current responsive means normally holding the other arm of said bell crank, resilient means for biasing the knee of said toggle linkage to collapsed open circuit position when said interrupter is in the closed circuit position, and means whereby said spring means biasing said switch member to the open circuit position holds the knee of said toggle linkage in the closed circuit position against said knee biasing means with said toggle links and said arm in straightened position with each making only a relatively small angle with the line between the points connected thereby, and said current responsive means being movable to release said bell crank and cause the collapse of said toggle linkage in the direction in which it is biased by said knee biasing means.

6. In a circuit interrupter, a stationary contact member, a pivotally supported switch member co-operating therewith to open and to close the electrical circuit through said interrupter, spring means biasing said switch member to the open circuit position when said interrupter is in the closed circuit position, an electro-responsive trip device, and an operating mechanism for actuating said switch member, said operating mechanism including a pair of toggle links pivotally joined together at one end by a knee pivot pin, the other end of one link operatively engaging said switch member and the other end of the second link engaging a releasable trigger means that is actuatable by said trip device, spring means biasing said knee pivot pin to the open circuit position when said interrupter is in the closed

circuit position, and means whereby the reactive force of said spring means biasing said switch member to the open circuit position holds said knee pivot pin in the closed circuit position 5 against said spring biasing means acting on said knee pivot pin, said knee pivot pin, when in the closed circuit position, being free to move under the biasing action of said spring means to the open circuit position when the reactive force of 10 the said biasing means falls below a certain predetermined value.

7. In a circuit interrupter, a stationary contact member, a movable contact member for cooperating therewith to open and to close the electrical circuit through the interrupter, resilient means supplying a predetermined pressure between the cooperating contact surfaces of said contact members, the reaction force of said resilient pressure securing means biasing said movable contact member toward the open circuit position when said interrupter is in the closed circuit position, and an operating mechanism for actuating said contact means, said operating mechanism including a toggle linkage the knee of 15 which is adapted to move to the over-center position when said switch means is moved to the closed circuit position, a movable member to which one end of the toggle linkage is pivoted, said movable member being biased to move to a 20 tripped position by the force of said resilient means biasing the movable contact to open circuit position, current responsive means normally retaining said movable member against said bias and being releasable to permit said movable contact 25 to move to open circuit position, and a spring means for biasing the knee of said linkage toward the open circuit position, said resilient means, said spring, and said linkage being so correlated that the reaction force of said resilient 30 means holds said linkage in the over-center, closed circuit position, against the biasing force of said spring, when said circuit interrupter is in the closed circuit position and normal contact pressure exists between said cooperating contact 35 surfaces, and being so correlated that when said contact pressure falls below a predetermined value said reaction force becomes incapable of holding said toggle linkage against movement toward the open circuit position under the biasing action of said spring.

8. In a circuit interrupter, a contact actuating member movable to an open and to a closed circuit position, means normally biasing said member to the open circuit position, a contact supported upon said contact actuating member, means biasing said contact toward the closed circuit position, at least when said interrupter is in the closed circuit position, means for holding said contact actuating member in the closed circuit position against the force of said first mentioned biasing means, and means responsive to the magnitude of the force biasing said contact to the closed circuit position for releasing said holding means when the magnitude of the force biasing said contact to the closed circuit position becomes less than a predetermined amount.

9. In a circuit interrupter, a contact actuating member movable to an open and to a closed circuit position, means normally biasing said member to the open circuit position, a contact supported upon said contact actuating member, spring means intermediate said contact and said contact actuating member which serves to bias said contact toward the closed circuit position, at 70 least when said interrupter is in the closed circuit 75 position.

circuit position, means for holding said contact actuating member in the closed circuit position against the reaction force of said spring means, and means responsive to the magnitude of the force exerted by said spring means tending to bias said contact to the closed circuit position for releasing said holding means when the magnitude of that force becomes less than a predetermined amount.

10. In a circuit interrupter, a contact actuating member movable to an open and to a closed circuit position, means normally biasing said member to the open circuit position, a stationary contact, a movable contact for cooperating therewith which is supported upon said contact actuating member, resilient means for biasing said movable contact toward said stationary contact at least when said interrupter is in the closed circuit position, said cooperating contacts engaging each other with a butt type engagement when said interrupter is in the closed circuit position, means for holding said contact actuating member in the closed circuit position against the force of said first-mentioned biasing means, and means responsive to the magnitude of the force biasing said movable contact toward said stationary contact for releasing said holding means when the magnitude of the force biasing said contacts into engagement with each other becomes less than a predetermined amount.

11. In a circuit interrupter, a stationary contact member, a movable switch means including a contact member for cooperating therewith to open and close the electrical circuit through said interrupter, spring means for supplying contact pressure between said cooperating members when said interrupter is in the closed position, a second spring means biasing said movable switch means to open circuit position, an operating mechanism for actuating said switch means, said operating mechanism including a toggle linkage connected to said switch means at all times and movable upon each movement of said switch means, a third spring means biasing the knee of said linkage to the open circuit position, said operating mechanism transmitting one component of the force exerted by each of the first two of said spring means to said knee of the toggle linkage for holding the knee of said linkage against movement to open circuit position by said third spring means, and the component of force exerted on the knee of said linkage by said second spring means alone being insufficient to prevent its movement to open circuit position whereby said third spring means moves the knee of the toggle to open circuit position upon a predetermined decrease in the force exerted by the first spring means for supplying contact pressure, and current responsive means normally in latching engagement with a part of said operating mechanism for preventing said second spring means from automatically moving said switch means to open the circuit and movable out of engagement with said operating mechanism for initiating movement of said operating mechanism and said switch means to open circuit position.

12. In a circuit interrupter, a pair of relatively movable contacts, a movable switch member for moving one of said contacts to open and close the circuit, spring means biasing said switch member to move to open position and biasing said contacts into pressure engagement, operating means for said switch member including three links, one of said links being pivoted to said switch member at a movable point thereon, another of said

links being pivoted at a fixed point, and the third of said links being pivotally connected between the first two links, means for manually moving one of said links to move said switch member to closed position, said links when in the closed position having the pivot points connecting them only a small distance away from the straight line between the point at which said one link is pivoted to the switch member and said fixed pivot point whereby the force of the bias of said switch member is largely transmitted to said fixed pivot point and there is only a small force tending to move the pivot points connecting the links away from said straight line, means providing a stop preventing the force of said bias from moving one of the pivot points connecting the links out of its closed position adjacent to said straight line, spring means biasing the last said pivot point of the links to move away from said stop and cause opening of the contacts, the last said spring means becoming effective to cause opening of the contacts after there has been a predetermined decrease in the pressure between said contacts, latching means normally engaging and holding one of said links to prevent the force of the first said biasing means from moving the other pivot point connecting the links out of its closed position adjacent said straight line, and said latching means being movable upon the occurrence of a predetermined electrical condition to disengage said link and permit the first said biasing means to move the switch member to open the circuit.

13. In a circuit interrupter, a pair of relatively movable contacts, a switch member for moving one of said contacts to open and close the circuit, spring means biasing said switch member to open position, operating means for said switch member including three links, one of said links being pivoted to said switch member at a point movable with the switch member, another of said links being pivoted at a fixed point, and the third of said links being pivotally connected at each end to one of the first two links forming two knee pivot points each movable to collapsed position, means for manually moving one of said links to move said switch member to closed position, said links when in the closed position having the knee pivot points connecting them not more than a small distance away from the straight line between the point at which said one link is pivoted to the switch member and said fixed pivot point whereby the force of the bias of said switch member is largely transmitted to said fixed pivot point and there is only a small force tending to move the knee pivot points connecting the links away from said straight line to collapsed position, means providing a stop preventing the force of said bias from moving one of the knee pivot points connecting the links from its closed position adjacent to said straight line to collapsed position, a latch member normally engaging and holding one of said links to prevent the force of said bias from moving the other of the knee pivot points from its closed position adjacent said straight line to collapsed position, and said latch member being movable upon the occurrence of a predetermined electrical condition to disengage said link and permit the biasing means to move the switch member to open the circuit.

14. In a circuit breaker, a pair of relatively movable contacts, a switching member for moving one of said contacts to open and close the circuit, spring means biasing said switching mem-

ber to move to open position, operating means for said switching member including three links forming a double toggle, one of said links being pivoted to said switching member at a point thereon which is movable with the switching member upon every movement thereof, another of said links being pivoted at a fixed point, and the third of said links being pivotally connected at each of its ends to one of the first two links to form the two knees of the double toggle, actuating means by which one of said links is movable to cause normal movement of said switching member to both open and close the breaker, said double toggle when in closed position being in substantially a straight line with one knee thereof under-set, current responsive latching means normally engaging and holding one of said links to prevent said under-set knee of the toggle from moving to collapsed position, said latching means being disengageable upon the occurrence of an abnormal condition to permit said knee of the toggle to move to collapsed position and cause movement of said switching member to open position, stop means holding the other knee of the toggle in over-set position when the breaker is closed, and the last said knee being movable between said over-set and collapsed positions upon movement of said actuating means to normally open and close the breaker without disengagement of said latching means.

15. In a circuit breaker, a pair of relatively movable contacts, a switching member for moving one of said contacts to open and close the circuit, spring means biasing said switching member to move to open position, operating means for said switching member including a pair of pivoted toggle links and a bell crank pivotally mounted at its apex and having one arm pivoted to one end of said pair of toggle links to form a double toggle therewith, actuating means by which one of said toggle links is movable to cause normal movement of said switching member to both open and close the breaker, said double toggle when in closed position opposing opening movement of said switching member and being in a substantially straight line so as to transmit most of the force biasing said switching member through the double toggle to a fixed point and so as to leave only small forces tending to collapse the double toggle at its knee pivots, current responsive latching means normally engaging and holding the other arm of the bell crank to prevent the knee pivot between the bell crank and the first said pair of toggle links from moving to collapsed position, said latching means being disengageable upon the occurrence of an abnormal condition to permit the last said knee pivot to move to collapsed position and cause movement of said switching member to open position, stop means holding the knee pivot of the first said pair of toggle links in over-set position when the breaker is closed, and the last said knee pivot being movable between over-set and collapsed positions upon movement of said actuating means to normally open and close the breaker without disengagement of said latching means from said bell crank.

16. In a circuit breaker, a pair of relatively movable contacts, a switching member for moving one of said contacts to open and close the circuit, spring means biasing said switching member to move to open position, operating means for said switching member including a pair of pivoted toggle links and a bell crank pivotally mounted at its apex and having one arm pivoted

to one end of said pair of toggle links to form a double toggle therewith, actuating means by which one of said toggle links is movable to cause normal movement of said switching member to both open and close the breaker, said double toggle when in closed position opposing opening movement of said switching member and being in a substantially straight line so as to transmit most of the force biasing said switching member through the double toggle to a fixed point and so as to leave only small forces tending to collapse the double toggle at its knee pivots, current responsive latching means normally engaging and holding the other arm of the bell crank to prevent the knee pivot between the bell crank and the first said pair of toggle links from moving to collapsed position, said latching means being disengageable upon the occurrence of an abnormal condition to permit the last said knee pivot to move to collapsed position and cause movement of said switching member to open position, stop means holding the knee pivot of the first said pair of toggle links in over-set position when the breaker is closed, and the last said knee pivot being movable between over-set and collapsed positions upon movement of said actuating means to normally open and close the breaker without disengagement of said latching means from said bell crank, and means for causing the knee pivot of the first said pair of toggle links to move from over-set to collapsed position upon release of said bell crank by its latching means to cause return of said actuating means to open position and to cause re-engagement of said bell crank with its latching means.

17. In a trip device for a circuit breaker, the combination of a rotatable trip shaft, and a pivoted latching member biased for movement from a latching to a releasing position having a latch tip normally engaging said shaft to restrain said latching member in said latching position, the pivot of said latching member and the axis of said shaft being so related that said latch tip tangentially engages said shaft to exert a substantially radial force thereon, whereby substantially no rotative movement is exerted on said shaft by said latching member, said trip shaft having a transversely extending notch therein through which said latch tip moves to said releasing position upon rotation of said trip shaft to a predetermined position.

18. In a trip device for a circuit breaker, the combination of a cylindrical trip shaft mounted

for rotation about a longitudinal axis, and a pivoted latching member biased for movement from a latching to a releasing position having a latch tip normally engaging the periphery of said shaft to restrain said latching member in said latching position, the pivot of said latching member and said axis of said shaft being so related that said latch tip tangentially engages the periphery of said shaft to exert a substantially radial force thereon, whereby substantially no rotative moment is exerted on said shaft by said latching member, said trip shaft having a transversely extending notch therein through which said latch tip moves to said releasing position upon rotation of said trip shaft to a predetermined position.

19. In a trip device for a circuit breaker, the combination of a rotatable trip shaft, and a pivoted latching member biased for movement from a latching to a releasing position having a latch tip normally engaging said shaft to restrain said latching member in said latching position, the pivot of said latching member being so related to said shaft that said latch tip moves along an arc passing substantially through the axis of said shaft, whereby substantially no rotative moment is exerted on said shaft by said latching member, said shaft having a transverse slot extending slightly more than half-way through said shaft so that upon rotation of said shaft to a predetermined position said latch tip is released for movement along said arc to said releasing position.

20. In a trip device for a circuit breaker, the combination of a cylindrical trip shaft mounted for rotation about a longitudinal axis, and a pivoted latching member biased for movement from a latching to a releasing position having a latch tip normally engaging the periphery of said shaft to restrain said latching member in said latching position, the pivot of said latching member being so related to said axis that said latch tip moves along an arc intersecting said axis, whereby substantially no rotative moment is exerted on said shaft by said latching member, said shaft having a transverse notch therein extending more than halfway through said shaft so that said latch tip may freely move along said arc when said shaft is rotated to a predetermined position to release said latching member for movement to said releasing position.
